ATTORNEY

UNITED STATES PATENT OFFICE

JAMES EDWIN PHILLIPS, OF NEW YORK, N. Y.

LOCKING PLATE

Application filed January 23, 1930. Serial No. 422,859.

This invention relates to locks and particularly to an improved set of locking plates whereby the lock associated therewith is made jimmy-proof.

The object of the invention is to provide a device which may be used with different forms of locks and which presents overlapping parts designed to prevent the entrance of a tool for prying the door open or moving any part of the lock to an inoperative position.

A further object of the invention is to provide a pair of coacting plates, one being adapted to be mounted on a door and the other on a jamb and the parts so interlocked that the jamb plate will overlap the operating parts of the door plate and the door plate in turn will interlock with the jamb plate to prevent any separation between the two plates.

In the accompanying drawings, Figure 1 is a longitudinal vertical sectional view through part of a door and part of a jamb with a pair of locking plates embodying the invention shown applied thereto, certain parts being broken away for better illustrating the construction;

Figure 2 is a fragmentary sectional view through Figure 1 on line 2-2.

Figure 3 is a sectional view through Figure 2 on line 3-3;

Figure 4 is a view similar to Figure 3 except that the door plate has been shown in position thereon;

Figure 5 is a view similar to Figure 1 but showing a slight modified structure;

Figure 6 is a side elevation of part of the locking jamb plate shown in Figure 5.

Referring to the accompanying drawings by numerals, 1 indicates a door, 2 a jamb, 3 a conventional lock operated by suitable lock-operating mechanism 4 of well known type secured in place by suitable screws or other means. On jamb 2 is a jamb plate 5 having an extension 6 provided with a suitable aperture for receiving a bolt of lock 3. A door plate 7 is mounted on door 1, said door plate being provided with a suitable boss for holding the outer part of the lock construction 4 in place. The boss 8 and parts near the

same are old and well known and therefore form no part of the present invention except in combination. The invention resides in the plates 5 and 7 at or adjacent the point where they interlock as shown in Figure 1. From Figures 1 and 4 it will be noted that the plate 7 is provided with an upstanding ridge or flange portion 9 and an inwardly extending section 10. Notches 11 and 12 are formed in section 10 as shown in Figure 4 so as to accommodate the ears or projections 13 and 14 of plate 5. These ears are preferably integral with the transverse section 15 of plate 5 as shown in Figure 1. An upstanding section 16 extends for the full length of section 15 and is provided with a flange 17 extending for a full length of section 16, said flange overlapping the thickened portion 9. This will positively prevent a jimmy from being forced between the interlocked portions of plates 5 and 7. By the arrangement of section 16 and flange 17 a recess 18 is presented as shown in Figure 2, said recess being adapted to accommodate the thickened portion or bar 9 while the lugs 13 and 14 extend through the notches 11 and 12, thus locking the parts together in such a way that they cannot be forced apart. It will be noted that the plates 5 and 7 are interlocked so that they cannot be forced apart and that any prying thereon attempting to force them apart will not in any way affect the retaining screws which hold either plate in position.

Instead of using plate 5 as shown in Figure 1, a different form may be used as shown in Figure 5 if desired. When the structure in Figure 5 is to be used, the plate 5 is cut off at the outer edge of the jamb 2 and a second plate 5' placed thereon, said second plate having an ear 19 and adapted to receive the swinging locking member 20. In this form of invention the plates 5 and 5' are both provided with openings 21 and 22 so as to receive a night latch and also a permanent locking bolt.

From this it will be seen that the flange from the keeper of any lock now on the market may be riveted onto plate 5, so that the jimmy-proof features of the present invention may be secured for all locks.

What I claim is:—

1. A pair of locking plates comprising a jamb plate and a door plate, said plates at their point of contact being formed with 5 interlocking projections so that when the jamb plate is in contact with the door plate the plates cannot be forced apart except in one direction, the interlocking projection on the jamb plate having an extending portion 10 provided with a flange overlapping the projections on said door plate.
2. A pair of locking plates comprising a door plate and a jamb plate, said door plate having a notched extension said jamb plate 15 being formed with a section provided with a pair of ears fitting into the notches of said notched extension and a flange overlapping said notch and the edge of said jamb plate.
3. A pair of locking plates of the character 20 described, comprising a door plate and a jamb plate, said door plate having an extension provided with a pair of notches and a thickened portion adjacent said notches extending for the full width of the door plate, said 25 jamb plate having a section fitting over part of the door plate and provided with a pair of ears fitting into said notches and with a combined upstanding section and flange overlapping said thickened portion of said door 30 plate.
4. The combination with a door jamb and a door of a pair of interlocking plates coacting with said door and door jamb, said locking plates comprising a door plate and a 35 jamb plate, said jamb plate having an opening for receiving the bolt of a lock and at the opposite end an upstanding section merging into an overhanging shoulder portion and into a pair of ears, said door plate being 40 provided with the apertured extension adapted to overlap the section of said jamb plate and accommodate the ears of said jamb plate, said door plate being also provided with a thickened portion extending for full length 45 and fitting into said overhanging shoulder portion.
5. A pair of locking plates of the character 50 described comprising a door plate and a jamb plate, said door plate having an extension provided with a pair of notches, said jamb plate having a section fitting over part of the door plate and provided with a pair of ears fitting into said notches and with a combined 55 upstanding section and flange overlapping the portion of the door plate carrying said notches.
6. A pair of locking plates of the character 60 described comprising a door plate and a jamb plate, said door plate having an extension provided with a pair of notches, a thickened portion spaced from the edge of said door plate and forming an upstanding flange extending from near one of said notches to near the other notch, said jamb plate having a section fitting over part of the door plate and 65

provided with a pair of ears fitting into said notches and a combined upstanding section and flange overlapping the thickened portion of said door plate.

Signed at New York in the county of New York, and State of New York this 21st day 70 of January, A. D. 1930.

JAMES EDWIN PHILLIPS.
